VACUUM CUP LIFTER FOR SHELL EGGS

Robert C. McCord, Romulus, Mich., assignor to Diamond International Corporation, New York, N.Y.

Filed Jan. 21, 1971, Ser. No. 108,689

Term of patent 14 years

Int. Cl. D8—05

U.S. Cl. D8—71

FIG. 2.

FIG. 1.

FIG. 4.

FIG. 3.

FIG. 1 is an elevational view of a vacuum cup lifter showing my new design;

FIG. 2 is a top plan view thereof;

FIG. 3 is a bottom plan view thereof; and

FIG. 4 is a cross-sectional view taken along line 4—4 of FIG. 3.

I claim:

The ornamental design for a vacuum cup lifter for shell eggs, as shown.
